CLAIM

The ornamental design for a cosmetic container, as shown and described.

DESCRIPTION

FIG. 1 is a perspective view of the cosmetic container, embodying our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom view thereof;

FIG. 8 is a cross sectional view taken along line 8—8 in FIG. 4; and,

FIG. 9 is a perspective view of the cosmetic container in an open position.

The broken lines shown in the drawings are for illustrative purposes only and form no part of the claimed design.
